APPARATUS FOR MANUFACTURE OF FIBERS OF INORGANIC THERMOPLASTIC MATERIAL

Åke Karl Erik Svende, Billesholm, Sweden, assignor to Hoganas-Billesholms Aktiebolag, Hoganas, Sweden, a Swedish company.

Application March 26, 1954, Serial No. 418,848.

Claims priority, application Sweden March 31, 1953

3 Claims. (Cl. 18—2.6)

This invention relates to an apparatus for the manufacture of inorganic fibers, particularly of glass, slag or other thermoplastic, inorganic material, in which a jet of the melted, fluid material is transformed into fine threads by the centrifugal effect of a rotating disk. In earlier known methods and apparatuses for this manufacture the fibers have been obtained as annular hanks, which have been taken down upon a table where they have been intermittently cut open with knives or scissors and removed. Rotating circular saw blades and knives rotating vertically or horizontally have sometimes been used for cutting the hanks open, in order to remove the fibers continuously.

This invention relates to an apparatus for collecting and removing the fibers formed.

The method of using the invention, which is based upon the use of a rotating centrifugal disk, is mainly characterized in that the fibers thrown out from the disk, immediately after having left the edge of the disk, are exposed to the action of a first stream of air, directed downwards at an angle to the vertical, so as to form staple fibers, and preferably somewhat later are exposed to the action of a second stream of air, directed more horizontally, whereafter the fibers, if desired, are coated with a liquid binder or lubricant. The binder or lubricant to be added is preferably dispersed in the horizontal stream of air, said stream of air thus transporting the binder or lubricant to the fibers.

The apparatus consists substantially of a centrifugal disk apparatus, common in this art, and is mainly characterized in a blowing fan impeller being provided upon the same shaft as the centrifugal disk, and under said disk, the blowing fan impeller consisting of two conical funnels partly pushed over each other, fan blades being provided in the interstice between the two funnels, so as to produce the first stream of air which is directed downwards at an angle to the vertical. The lower funnel is preferably at its lower edge provided with a circular flange, turned outwards and being provided with fan blades underneath, so as to produce the second, horizontally directed stream of air, which among other things shall prevent the fibers from sticking to the bottom of the mantle surrounding the impeller.

The invention will hereinafter be described more fully with reference to the attached drawing in which Fig. 1 illustrates an apparatus according to the invention in vertical cross section, and Fig. 2 is a top plan view of the centrifugal disk apparatus illustrated in Fig. 1.

The drawing shows a melting furnace 2 for the inorganic material from which fibers are to be made. The furnace has a bottom opening 4, through which the melted material passes as a fine jet. Under the bottom opening a centrifugal disk 6 is provided upon a shaft 26. A blowing fan impeller is provided on the shaft 26, under the disk 6, said blowing fan impeller consisting of two conical funnels 8, 10, the top angles of which are somewhat different. The upper funnel 8 is partly pushed over the lower funnel 10, and in the interstice between

2

these funnels which overlap each other in part, there are provided fan blades 16. The upper conical funnel 8 has for its purpose to direct the stream of fibers and to prevent the fibers from coming in contact with the fan blades. The funnel 8 thus protects the fan blades from being worn out. The fan impeller is surrounded by a mantle 12, arranged as a fan housing and provided with an outlet opening 14 for the fibers and the fiber-transporting streams of air. The lower edge of the lower conical funnel 10 is provided with a flange 22, turned outwards, fan blades 24 being provided under said flange so as to produce a horizontal stream of air along the bottom of the mantle 12, for preventing the fibers from coming in contact with and sticking to the bottom. The funnel 8 is supported on the funnel 10 by the inwardly extending projections 9 and the funnel 10 is supported on the shaft 26 through the bushing 11.

In manufacturing inorganic fibers it is often desirable to coat the fibers with a thin layer of a binder, lubricant or a similar agent. For adding such an agent in a liquid state, e. g. melted, dissolved or emulsified, the apparatus illustrated in the drawing is provided with the following device.

Within the lower conical funnel 10 a flange 18 secured thereto and extending inwardly is arranged so as to form a wedge-shaped channel between the flange and the inner wall of the funnel, said wedge-shaped channel having small interstices or openings in its bottom close to the inner wall of the funnel 10. The outlet opening of a pipe 20 for a liquid binder, lubricant or a similar agent is provided above or in said channel. The liquid agent will flow down along the inner wall of the conical funnel 10 to the fan blades 24, and will be thrown out by said fan blades 24 together with the horizontal stream of air, and will consequently come into contact with the stream of fibers coming from above. A similar feeding device for a lubricating or binding agent may of course be arranged in the upper conical funnel, the agent being thrown out by means of the fan blades 16. The apparatus illustrated in the drawing works in the following manner.

The inorganic thermoplastic material is melted in the furnace 2 and flows as a fine jet through the bottom opening 4 down upon the rapid-rotating centrifugal disk 6 where it is transformed into fine threads or fibers, which are thrown out from the disk. After having left the edge of the disk, the fibers will soon lose their horizontal speed and will fall downwards, thereby passing the stream of air induced by the suction action of the fan blades 16, the fibers being thus cooled. The fibers then are directed somewhat outwards by the upper conical funnel 8 and are caught by the stream of air, which is induced by the fan blades 16 and which is directed downwards at an angle to the vertical. By this means the fibers never have an opportunity of forming a hank, but are, in the form of staple fibers, directed by the stream of air past the two conical funnels 8, 10, and are then exposed to the horizontal stream of air, in which a lubricant or a binder may be dispersed and are at last discharged through the opening 14.

A uniform stream of a staple fiber product having very good qualities for the manufacture of felt and plates is produced in the apparatus according to the invention.

What we claim is:

1. Apparatus for the manufacture of fibers comprising a circular disk mounted for rotation on a vertical shaft, means for delivering a stream of thermoplastic, inorganic material in liquid state on to said disk, two spaced apart upwardly converging, overlapping, frusto conical members mounted on said shaft below said disk for rotation

therewith and fan blades positioned between said members and secured to at least one of them.

2. Apparatus as defined in claim 1 in which the lower edge of the lower of said two frusto conical members extends outwardly as a substantially horizontally disposed flange and fan blades are mounted on the lower surface of said flange. 5

3. Apparatus as defined in claim 2 comprising a flange secured to the inner surface of the lower of said frusto conical members and forming therewith a channel, openings between the outer edge of said flange and the inner surface of said member for the passage of liquid and a pipe positioned to deliver liquid into said channel. 10
